UNITED STATES PATENT OFFICE.

ELI J. McBRIDE, OF SAN FRANCISCO, CALIFORNIA.

HERNIAL TRUSS.

1,263,781.

Specification of Letters Patent. Patented Apr. 23, 1918.

Application filed May 7, 1917. Serial No. 166,871.

To all whom it may concern:

Be it known that I, ELI J. McBRIDE, a citizen of the United States, residing at San Francisco, in the county of San Francisco and State of California, have invented new and useful Improvements in Hernial Trusses, of which the following is a specification.

The present invention relates to improvements in trusses, the object of the invention being to provide a hernial truss which will be durable, comfortable and sanitary, which, while supporting a rupture on one side of the body will also prevent rupture on the other side, which will not get out of position, which will not interfere with any of the required movements of the body, or the performance of any of its organic functions, which will be simple in construction and free from set screws, steel bands and the like metallic parts, which can be worn with close-fitting clothes, without being noticeable by others, which can be adjusted to increase or decrease the pressure, by which the pressure will be caused to be over and around, instead of in, the aperture, thus assisting nature to close the aperture and heal the rupture, by the use of which the patient will never have strangulated hernia, because the hernia is kept in the bowel cavity where it performs its natural function unmolested, and which can be used either for a rupture on the right side or one on the left, or a double rupture, or prolapsus uteri in women. In the accompanying drawing, Figure 1 is a front or outside view of the truss, the parts being shown in the position of use; Fig. 2 is a broken view of the inner side of the truss; Fig. 3 is a cross sectional view, on the line 3—3 of Fig. 1.

Referring to the drawing, 1 indicates my improved truss body, which comprises, at the front side of the truss body, a frame of stiff cardboard, or similar strong and flexible material, a padding 2 of cotton or like yielding material behind said frame 1, and an outer casing 3 of leather. It is symmetrical on both sides on a vertical central line, along which line the front and back of the truss are brought nearer together than at the remainder of the truss body and are connected by a row of stitching 4. Consequently, the truss is able to bend along this central vertical line more freely than at other portions.

The truss is nearly rectangular in form,

but is narrower at the bottom than at the top. Secured on the front side of the truss, near its four corners respectively, are four pivot pins 5, to which are pivoted upper and lower hooks 6, 7, and at the center is a pivot pin 8, to which is pivoted a thin, narrow piece of metal 9, the ends of which are bent back on themselves to form hooks 10. Engaging the upper hooks 6 are loops 11 secured in the respective ends of an adjustable strap 12, by means of which strap the truss is adjustably secured around the body of the patient. The two lower hooks 7 engage eyelets 13 in the ends of a narrow leather band strap 14, which thus depends from the lower portion of the front of the truss. The band being provided with a plurality of eyelets, here shown as three, at each end, can be adjusted to any length desired. Extending over said band is a band 16, preferably made of tennis flannel, the ends of which are engaged by buckles 17 secured to ends of elastic straps 18. Loops 19 are secured to the other ends of said straps. The band 16 and straps 18 form a compound band, the sides of which, on opposite sides of the band 14, are passed rearwardly between the thighs, and around the hips to the front of the abdomen, the loops 19 being engaged by the hooks 10. A small ring or loop 21, of the same material as the band 16, surrounds the strap 14 and the middle portion of the band 16 where it passes over said strap, and thus prevents any friction between the middle of the band 14 and the adjacent parts of the body. The band 16 is so located that the lower portion of the band 14 is drawn rearwardly, thus pressing the lower portion of the truss against the lower portion of the abdomen, and furnishing an excellent support therefore, especially in cases of prolapsus uteri.

My improved truss contains many important advantages.

It is durable because there are no parts exposed to great wear, and the exposed parts can be made of material as substantial as may be desired. It is comfortable because the pressure is exerted equally on both sides of the body and because the arrangement of the band around the legs of the wearer produces an upward support, or pressure, by the lower part of the truss which carries the weight of the abdomen and is very comfortable to the patient. It can thus be used by women to great advantage for prolapsus

uteri. It is sanitary because there are no parts which can be affected by the excretions of the skin, so as to injure the health of the patient. Being entirely supported around the hips upon which the body turns in its movements, it does not interfere with any of the movements of the body, or the performance of the functions of any of its organs. It is free from set screws, steel bands, and the like metallic parts. The pressure can be increased or diminished, as desired. It will be observed that the truss instead of being in the form of a knob pressing directly against the ruptured part, is in the form of a pad on each side pressing over and around the aperture. Being symmetrical in form, it can be used either for a rupture on the right side or for one on the left side, or for ruptures on both sides. For the same reason, when used to support a rupture on either side of the body, it will also prevent rupture on the other side. Also for the same reason, it can be worn with close-fitting clothes without being noticeable by others. With my invention the hernia is retained in the bowel cavity, so that a wearer can never have strangled hernia.

I claim:

1. A truss having on its outer surface hooks at the lower portion of the truss, and upper hooks above the first-named hooks, a

strap attached to said truss and extending around the body of the patient, a band attached at its ends to the lower hooks, and a second band extending over the middle portion of said lower band, the ends of which are attached to said upper hooks. 35

2. A truss having on its outer surface hooks at the lower portion of the truss, and upper hooks above the first-named hooks, a strap attached to said truss and extending around the body of the patient, a band attached at its ends to the lower hooks, a second band extending over the middle portion of said lower band, the ends of which are attached 40 to said upper hooks, and a ring of flexible material around said bands. 45

3. A truss having hooks pivoted thereto symmetrically on opposite sides of the upper portion of its outer surface, hooks pivoted thereto symmetrically on opposite sides of the lower portion of said surface, hooks formed in a single piece pivoted at the center of said surface, said latter hooks extending in opposite direction, from said center, a 55 strap having at its ends means for engaging the first-named hooks, a band having means at its ends for engaging said last-named hooks, and a band having at its ends means for engaging the second-named hooks and 60 passing around said last-named band. 50
